UNITED STATES PATENT OFFICE

2,440,826

BRASSIÈRE

Jack J. Lo Cascio, Bayonne, N. J., assignor to
Even-Pul Foundations, Inc., New York, N. Y.,
a corporation of New York

Application May 2, 1945, Serial No. 591,448

3 Claims. (Cl. 2-42)

1

This invention relates to brassières, and more particularly to a garment of this kind having resilient means to yieldingly support the breasts in a lifted position.

Another object of the invention is to provide, in combination with a brassière having breast-receiving cups, elastic straps extending across the lower portions of the cups so as to pass under the breasts and yieldingly support them in a lifted position.

A still further object of the invention is to provide elastic breast-supporting straps which are so constructed and arranged as to support the breasts in a lifted position without any discomfort to the wearer.

Still another object of the invention is to provide a brassière having a front portion provided with a central elastic insert at a zone between the breast-receiving cups and provided with reinforcing tapes along the upper edges of the insert, said edges and tapes being formed to provide fullness and insure comfort to the wearer.

The exact nature of the present invention will become apparent from the following description when considered in connection with the accompanying drawing.

In the drawing:

Figure 1 is a front elevational view, in opened condition, of a brassière constructed in accordance with the present invention.

Figure 2 is a rear elevational view of the brassière as shown in Figure 1.

Figure 3 is a section taken on line 3—3 of Figure 2.

Figure 4 is a section taken on line 4—4 of Figure 2.

Referring in detail to the drawing, the body of the garment is of general vertically narrow and horizontally elongated form, and is composed of substantially similar end sections 5 and 5a having central elastic gussets 6 and 6a inserted in the lower portions thereof; an upper front portion including similar upper front sections 7 and 7a formed to provide breast-receiving cups; a central elastic insert 8 in the lower edge of said upper front portion; and a lower front band portion 9 stitched to the lower edges of the upper front sections 7 and 7a and the elastic insert 8. The upper front portion is cut out to receive the insert 8, and upwardly diverging darts 9a are provided at opposite sides of the cut out to give the desired shape to the breast-receiving cups.

The elastic insert 8 has downwardly curved and diverging upper edges 10, and downwardly curved and diverging reinforcing tapes 11 are stitched

2

to the edges 10 and the edges of the upper front sections 7 and 7a meeting therewith. This construction provides strength, elasticity and fullness where the cups join at their adjacent lower portions.

The outer or free vertical edges of the end sections 5 and 5a are respectively provided with hooks 12 and eyes 13 to facilitate connection of the ends of the brassière at the back, there preferably being two rows of eyes 13 for adjustment. Also, the sections 5 and 5a have upward extensions 14 to which are attached corresponding ends of shoulder straps 15. The sections 7 and 7a also have upward extensions 16 to which are attached buckles 17 adapted to coact with the shoulder straps 15 so that the latter may be adjusted to suit the requirements of the wearer. To the lower edge of the garment are attached supporters 18 that may be detachably engaged with the upper edge of a girdle when one is worn by the user of the brassière.

Extending across the lower portions of the cups formed by the sections 7 and 7a are elastic straps 19 arranged to pass under the breasts and yieldingly support the same in lifted position. These straps 19 are attached at their opposite ends to opposite sides of the cups, and said straps are disposed in downwardly diverging relation, as shown in Figure 2. The arrangement is such that the desired support is effectively provided in a way to insure maximum comfort to the wearer. Such comfort is further insured by constructing each of the straps 19 of inelastic end sections 20 of pile fabric and an intermediate elastic section 21. By the use of the straps 19, the breasts are supported in a most desirable manner, and it is not necessary for the cups to have an accurate fit as to form and size.

From the foregoing description, it is believed that the construction and advantages of the present garment, as well as the manner in which the same functions, will be readily understood and appreciated by those skilled in the art. The garment is simple and efficiently provides the desired characteristics. Minor changes may be made in the form and construction of parts illustrated and described, such as fairly fall within the scope of the invention as claimed.

What I claim is:

1. A brassière comprising a horizontally elongated body composed of a front section and substantially similar end sections and adapted to be secured around a wearer, said front section comprising an inelastic lower under-breast band portion and an upper portion shaped to provide

breast cups, and downwardly diverging elastic breast supporting and separating straps extending across the inner surface of the lower portions of the breast cups and permanently attached at their outer ends to the outer sides of the upper portion near the bottom of the latter and at their inner ends to the vertical center of said upper portion near the top of the latter, said straps being free of connection with said upper portion except at their ends.

2. A brassière comprising a horizontally elongated body composed of a front section and substantially similar end sections and adapted to be secured around a wearer, said front section comprising an inelastic lower under-breast band portion and an upper portion shaped to provide breast cups, said upper portion including a main inelastic part and a central horizontally yieldable elastic insert in the lower edge of said inelastic part and attached to the upper edge of said under-breast band portion, said insert being horizontally elongated and having upper downwardly curved edges which extend in downwardly diverging relation from the inner sides of the breast cups substantially to the centers of the latter.

3. A brassière comprising a horizontally elongated body composed of a front section and substantially similar end sections and adapted to be secured around a wearer, said front section comprising a lower band portion and an upper por-

tion shaped to provide breast cups, said upper portion including a main inelastic part and a central horizontally yieldable elastic insert in the lower edge of said inelastic part, said insert being horizontally elongated and having upper downwardly curved edges which extend in downwardly diverging relation from the inner sides of the breast cups substantially to the centers of the latter, and downwardly diverging elastic breast supporting and separating straps extending across the lower portions of the breast cups and permanently attached at their outer ends to the outer sides of the upper portion near the bottom of said upper portion and at their inner ends to the vertical center of the upper portion near the top of said upper portion, said straps being free of connection with said upper portion except at their ends.
